CONTAINER CLOSURE STRUCTURE

William Martin Vogel, Glenn Ridge, and Robert Woods Fentress, Elizabeth, N. J., assignors to Stanco Incorporated

Application August 4, 1930, Serial No. 472,906

1 Claim. (Cl. 220—27)

This invention relates to improvements in the sealing of containers. The invention will be fully understood from the following description taken in connection with the accompanying drawing 5 in which latter,

Fig. 1 is a transverse section through a container showing a closure applied thereto in temporary position;

Fig. 2 is a top plan view of the closure; and 10 Fig. 3 is a transverse sectional view showing the closure permanently affixed to the nozzle of the container and a cover secured to the nozzle.

Referring particularly to the drawing, reference numeral 1 designates the body of a container and 15 2 designates a nozzle projecting from and of less diameter than the top of the body. The end of the nozzle is inset preferably as indicated at 3 and terminates in a flange 4 which extends outwardly from the inset portion of the nozzle. The 20 nozzle can be fastened to any convenient part of the container to facilitate filling and emptying of the container. The nozzle is preferably disposed in a vertical position.

A sealing disk or cap 6 constitutes a closure 25 for the nozzle. As shown in Fig. 1 the cap has laterally extending sidewalls 7 which engage the inner wall of the end of the nozzle. The cap is provided with a marginal flange 8 which terminates in a downwardly and radially inwardly extending portion 9. The cap is preferably formed by stamping the same from a sheet of metal 30 which has been previously coated with a dry flexible compound such as lacquer. The cap is preferably formed of relatively thin material to facilitate piercing of the cap when it is desired to pour 35 out the contents of the container.

In securing the cap to the nozzle the cap is first disposed loosely upon the end of the nozzle as shown in Fig. 1. A liquid tight joint is effected 40 between the nozzle and the cap by pressing metallic disks, not shown, revolving in a horizontal plane, against the outer edge of the cap with sufficient pressure to roll the flange 4 of the nozzle and the flange 8 and portion 9 of the cap together 45 to form a seal. As seen in Fig. 3 the flange of the nozzle then extends radially outwardly and backwardly in spaced relation to the inset portion of the nozzle, and the marginal portion of the cap projects downwardly around and upwardly under the flange to form a double seam disposed 50 exteriorly of the nozzle. In the preferred embodiment the seam engages the inset portion of the nozzle. The seam lies within the periphery of the body portion of the nozzle.

55 A cover 10 has interlocking engagement with

the nozzle by means of screw threads or the like which are adapted to engage one or more projections 11 disposed upon the body portion of the nozzle. The cap when permanently affixed to the nozzle is provided with an outwardly projecting portion 12 which forms an annular seat for the cover to facilitate the formation of a liquid tight connection of the cover 10 with the nozzle to prevent leakage of liquid after the cap is perforated.

In the construction described the upwardly projecting nozzle facilitates the filling of the container with liquid. The cap is sealed to the nozzle by an outside seam which can be formed after the container is filled and the seam is so constructed that it will withstand considerable internal pressure. The cap can be easily applied to the nozzle and being formed of relatively thin material it can be readily broken when the contents of the container are to be used, but cannot be replaced, thereby preventing refilling of the 75 container in its original form.

Various changes may be made within the scope of the appended claim in which it is desired to claim all novelty inherent in the invention as broadly as the prior art permits.

We claim:

A container comprising a body, a nozzle projecting from and of less diameter than an end of the body, a cover, the free end of the nozzle being inset peripherally and terminating in a flange which extends downwardly and backwardly with its margin facing backwardly in spaced relation to the inset portion of the nozzle, a cap of relatively thin material having a laterally extending portion engaging the inner wall of the nozzle and an outwardly projecting portion forming an annular seat for the cover, and a marginal portion exteriorly double seamed with the flange forming a permanent fluid tight seal, the seal lying within the periphery of the body portion of the nozzle, and means associated with the nozzle laterally of the inset portion and between the cap and the body for interlocking engagement with a cover extending in spaced relation to the portion of the cap enclosed by the annular seat.

WM. MARTIN VOGEL.
